UNITED STATES PATENT OFFICE.

ROBERT P. GREENLEAF, OF SHAKER HEIGHTS, OHIO, ASSIGNOR TO FRANK BILLINGS,
OF CLEVELAND, OHIO.

LOADING SYSTEM.

Application filed March 12, 1924. Serial No. 698,632.

To all whom it may concern:

Be it known that I, ROBERT P. GREENLEAF, a citizen of the United States, residing at Shaker Heights, in the county of Cuyahoga and State of Ohio, have invented a certain new and useful Improvement in Loading Systems, of which the following is a full, clear, and exact description.

This invention relates to a car loading system and is an improvement over the subject matter of an application, Serial No. 621,999, filed March 1, 1923, in the name of Frank Billings and myself; also the subject matter of my application, Serial No. 688,678, filed January 26, 1924.

The loading systems disclosed in both said applications are for the purpose of loading a series of cars from a loading machine, and involves the use of a skip designed to receive the material from the loading machine, and arranged to travel over supporting rails provided on the tops of the cars to be filled. In both the applications referred to, the rails which are adapted to support and guide the skip are continuous in the sense that they bridge the gaps between the cars, though the rails or skip trackway are in both instances so formed that they will accommodate themselves to curves of the tracks such as mine tracks over which the cars are adapted to be moved, and permit the loading of the cars even though they are positioned on a curve of the track.

The principal object of the present invention is to do away with the necessity of continuous rails or of rail sections between the cars, and at the same time to avoid liability of the skip dropping into the gap between any two cars, and to provide also, means for not only avoiding derailment of the skip in the event the cars are located on a curve of the track, but to properly guide and deflect the skip from one car to another, with the cars arranged at an angle as they may be when standing on a curve.

The invention may be further briefly summarized as consisting in certain novel details of construction, and combinations and arrangements of parts which will be described in the specification and set forth in the appended claims.

In the accompanying sheets of drawings wherein I have shown two embodiments of the invention, Fig. 1 is a side elevation of two cars of a series, also the skip and the

power unit adapted to support the skip when in loading position and to move the same back and forth over the cars; Fig. 2 is a sectional view of the skip and a portion of the supporting rail showing the body extended for dumping the skip into a car; Fig. 3 is a detail of a stop adapted to be clamped to a car at the dumping point to trip a latch and thereby release the body portion and base of the skip; Fig. 4 is a top plan view of a series of cars provided with skip rails formed in accordance with one form of the invention showing part of the cars arranged on a curve, and illustrating the manner in which the skip rails individual to the different cars are relatively arranged when the cars are on curved as well as straight portions of a track; Fig. 5 is a front end view of the skip; Fig. 6 is a view of the opposite end of the skip with the skip supported on one of the cars which is in vertical section; Fig. 7 is a bottom view of the skip showing particularly the rollers employed with a car trackway of the form shown in the preceding figures; Figs. 8, 9 and 10 are plan views, somewhat diagrammatic, illustrating how the skip passes from one car to another, both when the cars are on a curve (Figs. 8 and 9) and when on a straight track (Fig. 10); Fig. 11 is a top plan view; Fig. 12 is a side elevation showing the power unit and one car with the reverse arrangement of rollers and tracks to that illustrated in the preceding views, this modification showing the power unit and cars provided with supporting and guiding rollers and the skip, with the equivalent of rails adapted to engage and travel over these rollers; and Fig. 13 is an end view on an enlarged scale showing the skip of Figs. 11 and 12 and the upper part of the car in section.

Any suitable loading machine may be utilized to fill the skip, and the cars to be filled may be located either to the rear or at one side of the loading machine.

The loading system includes a skip adapted to travel over a series of cars 11 adapted to be coupled together and conveyed to and from the loading point by a locomotive or other suitable means. In the drawings I have illustrated typical mine cars, as the invention is particularly adapted for mine use, though not confined thereto.

As in my prior application I have here illustrated a so-called power unit 12 on which

the skip is supported while being loaded, this power unit being provided with motor or engine driven drums 13 and 14 for the tail rope 15 used to retract the empty skip, and for the main rope 16 for moving the loaded skip back over the cars. The rope system for shifting the skip is substantially the same as that illustrated in the Billings and Greenleaf application, Serial No. 10 621,999, and need not therefore be described in detail, it being understood that the cars are provided at the top with pulleys or sheaves 17, which guide the ropes when the cars are going about or positioned on a 15 curve.

Some of the details of the skip, however, will be pointed out presently, and I will later describe the manner in which the skip is dumped, though the method of dumping is 20 similar to that shown in application, Serial No. 621,999.

As already stated, in accordance with the present invention the trackway or supporting devices provided at the tops of the cars 25 are individual to the different cars and are unconnected between the cars; that is to say, continuous trackways are eliminated, this being particularly useful as it admits of the dumping of the cars in any suitable 30 fashion and in any of the ways for which the cars are by their construction adapted.

In accordance with the preferred form of the invention, the cars and the power unit are provided with rails to accommodate the 35 skip, and the latter is provided with rollers adapted to run over these rails, and with other rollers adapted by engagement with the rails to guide the skip along the cars when the latter are on a straight track and 40 to deflect the skip when the cars are on a curve, and this embodiment of the invention is illustrated in Figs. 1 to 10. In this embodiment the inclined skip tracks on the power unit are indicated at 18, and the skip 45 tracks on the cars 11 are indicated at 19. These tracks are preferably formed by angles, with the skip adapted to engage up- 50 standing flanges of the angles, which flanges may be reinforced at the top by reinforcing strips such as shown at 20 in Fig. 6. It is a feature of the present invention that the tracks 19 are extended in both directions beyond the ends of the cars and beyond the rear end of the power unit so as to decrease, 55 as much as possible, the gap between the cars or between the power unit and the adjacent car. In order that maximum extensions 60 may be provided without interfering with the movement of the cars around a curve of the track, and also for the purpose of forming deflecting guides for the skip, as will be explained, the ends of the tracks or track sections 18 where they project beyond the power unit or beyond the ends of the cars 65 are curved inwardly as shown at 20. It

will be seen, particularly by reference to the two rearmost cars of Fig. 4, that when the cars are in alignment, the inwardly curved rails on one car are close to the corresponding ends of the rails of the adjoining car, the distance between the rail ends being considerably less than the distance between the car ends, and it will be observed also, that these inwardly curved ends of the rails do not interfere with the arrangement of the cars at a decided angle with respect to each other when the cars are on a curve. It may be here stated, that the design of the rail ends in regard to the distance that they project beyond the cars and 75 their curvatures will be such as to admit of the passage of the train of cars around a curve of the shortest radius of any particular track system.

Not only do the rail ends at each end of 80 each car curve inwardly toward each other, but they preferably also are inclined or tapered downwardly toward their free ends, as illustrated in Figs. 1 and 6. This downward inclination is provided to enable the 85 skip to pass from one car to another notwithstanding slight inequalities in the level or height of the skip track rails on the different cars, which inequalities might be due to variations in the level of the track over 90 which the cars are run, or to variations in the height at which the car bodies are supported by the running gear of the cars.

To co-operate with skip track rails such as described, the under side of the skip 10 is 95 provided with a series of broad faced wheels or rollers 21 which engage or travel over the skip tracks. The faces of these rollers are sufficiently long that they will engage, and therefore support the skip while traveling over the inwardly curved ends of the rails as well as the straight portions thereof, and a sufficient number of these rollers 21 is provided so that the skip will be adequately supported when passing from the 100 rails of one car to the rails of the other, whether the cars are in alignment or at an angle to each other, thereby avoiding liability of the skip dropping in between the cars. This is apparent from Figs. 8, 9 and 10. I 105 prefer to use more than two sets of the rollers 21 to accomplish the result just stated, and have illustrated in Fig. 7, four sets of rollers.

Additionally the skip is provided with a 110 plurality of sets of vertically disposed rollers 22, which project downward on the outer sides of the skip rails, the function of these rollers being to guide the skip along the skip rails so as to prevent its derailment, 115 and also to deflect the skip as the skip passes from one car to another when they are angularly disposed and not in alignment. This deflection of the skip, and 120 therefore its change of position and direc- 125

tion of travel in passing from one to the other of two angularly disposed cars is caused by the engagement of the rollers 22 with the inwardly curved ends 20^a of the 5 skip track rails as is apparent from a consideration of Figs. 8 and 9.

It will be seen, therefore, that though the skip rails at the tops of the cars are not continuous, the skip will pass readily when 10 operated by the head and tail ropes from one car to the other over the gaps between the cars, regardless of whether the cars are in alignment, as when on a straight track or are at angles with respect to each other, 15 as when on a curved track. It might be stated also, that the friction due to the engagement of the guiding and deflecting rollers with the skip rails is not excessive and the skip can be pulled along over the 20 cars readily, regardless of how they are relatively positioned.

The same results as explained above can be obtained by reversing the arrangement of the rollers and rails as illustrated in 25 Figs. 11, 12 and 13. As shown in these figures, the power unit and cars are provided with horizontally disposed supporting rollers 23 and 24, the former being short faced rollers mounted on studs on horizontal roller supports 25 provided along the upper side 30 edges of the cars and power unit. The rollers 24 are long faced rollers which are arranged at the end of the power unit and at the ends of the cars, these rollers projecting beyond the ends of the power unit 35 and cars and being inclined as illustrated, so as to decrease the gap to be bridged by the rails or shoes on the skip, and at the same time to allow the cars to accommodate 40 themselves to track curves. Additionally the power unit and cars are provided with vertical guiding and deflecting rollers 25, and at the ends they are provided with vertical deflecting rollers 26 set in toward the 45 center line of the power unit and cars.

With this arrangement the skip is provided at the bottom with shoes 27, the lower faces of which ride over the rollers 23 and 24 and the sides of which engage rollers 25 50 and 26, these shoes being on the inner side of rollers 25 while the rollers 26 are positioned inside the shoes, as shown in Fig. 13.

The shoes 27 are tapered at their ends, as 55 illustrated in Fig. 13, and at their ends the bottom faces are curved upwardly, as shown in Figs. 12 and 13. By the engagement of the tapered ends of the shoes with the vertical rollers, the skip will be deflected when the cars are on a curve precisely as with the 60 arrangement first described, and by the provision of the long faced rollers which project beyond the ends of the cars and power unit and are inclined inwardly so as not to interfere with the swinging movement of the 65 cars when they round a curve, the skip will

be properly supported in passing from one car to another, whether the cars are in alignment or at an angle to one another.

As already stated, the skip is operated, i. e., moved back and forth over the cars and dumped substantially as in the application, Serial No. 621,999, but the structure of the skip has been modified somewhat, and this will now be described.

The skip is provided with a base 28, carrying the rollers 21 and 22 of the construction first described, or the shoes 27 of the modification. Likewise, it includes a body portion 29 capable of moving over or along the base, as illustrated in Fig. 2, to dump the skip, the body portion being normally held and latched over the base by a pivoted latch 30 which is normally hooked over the rear end 31 of the base. This latch, which is located at the center of the forward end of the body portion of the skip, is carried by a rock-shaft 32, having at its outer end (see Fig. 5) an offset pin 32^a.

At the sides of the body portion of the skip are wheels 33 which engage horizontal rails 34 arranged along the sides of the base of the skip, the arrangement being such that the body portion may travel back over the base when the latch 30 is disengaged.

The head rope 16 is attached to an anchorage member 35 at the rear end of the body portion of the skip, as shown in Fig. 2, and from this point it passes back to the rear end of the rearmost car around a sheave 36, and then forwardly to the drum 14.

The tail rope 15 is fastened to an anchorage member 37 (see Fig. 2) on the base of the skip, and then passes around a sheave 38 at the rear end of the body portion of the skip (see Fig. 2) and then extends to the tail rope drum 13.

The dumping of the skip at any particular point in its travel is determined by a stop 39, adapted to be clamped at any desired point to one of the skip rails 19 on any of the cars. When the skip is traveling rearwardly this stop 39 is adapted to be engaged by a latch releasing rod or slide 40 carried by the base part of the skip. This bar which is supported for sliding movement along one side of the base of the skip is normally retracted or held in its rearwardmost position by a spring 41. When the rearward down-turned end of this bar engages the stop 39, wherever it may be positioned, the bar is pushed forwardly along the base of the skip, and its tapered forward end engages under the offset pin 32^a, on the latch supporting rock-shaft 32, and rocks this shaft so as to shift the latch to releasing position. The base of the skip is now held stationary by the stop 39, but the continued pull on the head or main rope

16 slides the body portion of the skip rearwardly beyond the base so as to dump the contents of the skip into the car to which the stop 39 was applied.

5 When the drums 13 and 14 of the power unit are reversed so as to wind in on the tail rope and pay out the head rope, the body portion of the skip first slides forwardly to normal position on the base and 10 becomes latched thereto. Thereupon the skip is hauled back and comes to a stop on the inclined rails of the power unit. When in this position it is loaded by the loading machine and the operation is repeated.

15 While I have shown two forms of my invention, I do not desire to be confined to the exact details shown, but aim in my claims to cover all modifications which do not involve a departure from the spirit and scope 20 of my invention as defined in the appended claims.

Having described my invention, I claim:

1. In a loading system, a series of cars, and a skip adapted to travel over the cars, 25 the cars having skip supporting members individual to the different cars and arranged to permit the cars to swing relatively in passing a curve and to permit a skip to pass from car to car while said cars are on a 30 curve.

2. In a loading system, a series of cars to be filled, and a skip adapted to travel over the cars and to dump its contents therein, the cars being provided with skip supporting members which are unconnected between 35 the cars and which project beyond the ends of the cars so as to reduce the gap to be bridged by the skip, the projecting portions permitting the cars to swing relatively on 40 a curve of the track.

3. In a loading system, a series of cars adapted to be filled, and a skip for filling the same adapted to travel over the tops of the cars, the skip and cars having co-operating 45 supporting and guiding members, the members on the cars being individual thereto and unconnected therebetween and arranged to deflect the skip when the latter is passing between cars arranged at an angle to 50 each other.

4. In a loading system, a series of cars, and a loading skip adapted to travel over the same, the cars being provided with skip 55 supporting members, said members being inclined inwardly at the ends of the cars.

5. In a loading system, a series of cars, and a loading skip adapted to travel over the same, the cars being provided with skip supporting members, said members projecting beyond the ends of the cars, the projecting portions being inwardly inclined. 60

6. In a loading machine, a series of cars to be filled, and a skip for filling the same adapted to travel over the tops of the cars, the cars being provided with skip supporting rails which are unconnected between the cars and which project beyond the ends of the cars and are inclined inwardly. 65

7. In a loading machine, a series of cars to be filled, and a skip for filling the same 70 adapted to travel over the tops of the cars, the cars being provided with skip supporting rails unconnected between cars and the skip having wheels or rollers adapted to engage the same, said rails having portions 75 for deflecting the skip in passing between cars with the latter arranged at an angle with respect to each other.

8. In a loading machine, a series of cars to be filled, and a skip for filling the same 80 adapted to travel over the tops of the cars, the cars being provided with skip supporting rails curved inwardly at their ends and projecting beyond the ends of the cars.

9. In a loading machine, a series of cars 85 to be filled, and a skip for filling the same adapted to travel over the tops of the cars, the cars being provided with skip supporting rails curved inwardly and tapered downwardly at their ends. 90

10. In a loading system, a series of cars provided with skip supporting rails with portions along the sides of the cars and other portions adjacent the ends of the cars forming relatively close skip supports, and 95 a skip adapted to travel over the rails and of sufficient length to engage the relatively close as well as the relatively widely spaced portions of the rails.

11. A loading system comprising a plurality of cars having skip supporting rails with main portions along the sides of the cars and with relatively close portions projecting beyond the ends of the cars, and a skip adapted to travel over the rails and 100 adapted to engage both said portions of the rails. 105

In testimony whereof, I hereunto affix my signature.

ROBERT P. GREENLEAF.
